REINHOLD H. WAPPLER, OF NEW YORK, N. Y.

CYSTOSCOPE.

No. 874,810.

Specification of Letters Patent.

Patented Dec. 24, 1907.

Application filed March 26, 1907. Serial No. 364,306.

To all whom it may concern:

Be it known that I, REINHOLD H. WAPPLER, a citizen of the United States, residing in the borough of Manhattan, city, county, and State of New York, have invented an Improvement in Cystoscopes, of which the following is a specification.

Heretofore, cystoscopes or instruments employed in the diagnosis and treatment of diseases of the urinary organs, have commonly comprised a sheath, a telescopic tube fitted in the said sheath, means between the sheath and the telescopic tube forming ways for the catheter tubes employed, and means operative and adjustable longitudinally of the telescopic tube for directing the path of the extremity of a catheter tube in inserting the same into a canal into which it is to be passed. As heretofore constructed however, it has always been necessary, so far as I am aware, to pass the cystoscope into and through the urethra in an inverted position and to then turn the same around in order to have it in the position for use, and this in and of itself, is a very painful procedure; moreover, there has been a certain element of danger in the use of these instruments as hereinbefore constructed, because of the liability of the parts thereof injuring the walls of the organ into which the instrument has been inserted.

Now the object of my present invention is to obviate the hereinbefore named difficulties, and in carrying out the same, I employ a sheath, a telescopic tube, means for conducting and guiding a catheter, and a revolvably operated means for directing the paths of the ends of the catheters,—as will be hereinafter more particularly described.

In the drawing, Figure 1 is an elevation of my improved cystoscope showing the parts assembled and broken away. Fig. 2 is a cross section on line x, x , Fig. 1. Fig. 3 is a cross section on line y, y , Fig. 1. Fig. 4 is an elevation of the telescopic tube forming part of the cystoscope. Fig. 5 is an inverted plan of the same. Fig. 6 is a partial inverted plan, showing the guide bar turned to the position in which the end of the catheter is directed from a straight line path, and Fig. 7 is a cross section on line z, z , Fig. 1, showing the guide bar turned out of its right line position.

Referring to the drawing, a represents a sheath, preferably tubular and provided with an end portion b connected thereto or integral therewith and set at an angle to the body

portion of the sheath a . The end portion b is preferably provided with cut-away parts 12 on the opposite sides thereof and with a removable cap b' adapted to contain an electric light bulb 13 to be received within the end of the off-set end portion b . The end of the sheath a , adjacent to the off-set portion b and in line with the under cut-away part 12 of the end b , is also provided with a cut-away part a' and on the other end of the sheath a is a head 10 provided with a clamp or set screw 11.

c represents a telescopic tube, one end of which is provided with an eye-piece 14, adjacent to which is a stop 15, secured on which is a clamp member 16. At one end of the telescopic tube is a lens 17 and at the other end a lens 18, and as will be understood, intermediate lenses may be employed if so desired. The telescopic tube c is adapted to be passed into the sheath member a ; and the stop 15 to abut against the head 10, the clamp member 16 passing under the set screw 11, which is turned down thereon and by which means the telescopic tube member may be maintained in the proper position within the sheath a .

On one side of the telescopic tube and running parallel therewith and parallel to each other, I prefer to employ a pair of tubes d, e , the inner ends of which terminate at a point appreciably distant from the place wherein the lens 17 is set,—these tubes passing through the said head 10 and having their opposite ends passed around the telescopic tube c and terminating on the opposite side thereof. These tubes d, e , are adapted to receive and guide the catheters d', e' , which are passed into the tubes from the outer ends thereof.

Between the tubes d, e , and on the under side thereof, I employ a rod f , journaled in suitable bearings 19 secured to the said tubes d, e . One end of this rod f adjacent to the inner ends of the tubes d, e , is flattened as at f' and carries a guide bar g which is pivotally connected thereto by means of the pin 20 or otherwise.

As indicated in Figs. 1, 3 and 6, the opposite sides of the guide bar g are recessed longitudinally, preferably corresponding to the curve of the respective tubes d, e , so that in the positions shown in Figs. 1 to 5 inclusive, the catheters d', e' , having been passed through their respective tubes or guide ways d, e , will assume a position with their ends

lying within the recessed sides of the said guide bar *g*.

The opposite end of the rod *f* is provided with a head member 21, secured to which is a handle 22, and the head member 21 is preferably journaled in a bearing 23 secured to the telescopic tube *c* between the stop 15 and the eye-piece 14.

Now in the use of the hereinbefore described instrument, the sheath member *a* is passed into and through the urethra to the bladder of the patient and as hereinbefore stated, the instrument is inserted in the position in which it is necessary to use the same; 15 thereupon the telescopic tube *c* is passed to place within the sheath *a*, the catheters having previously been placed into the tubes *d*, *e*, to approximately the positions shown in Figs. 4 and 5; thereupon the handle 22 may 20 be turned to turn the rod *f* and thereby cause the guide bar *g* to move and determine the direction of the path of the end of either catheter *d'*, *e'*, the side to which the handle 22 is turned, depending upon which catheter 25 is to be directed. By this it will be apparent that the catheters may be directed to and passed into the ureter canals and if necessary passed right up to the pelves of the kidneys.

As hereinbefore stated, the longitudinal grooves or recesses in the opposite sides of the guide bar *g* are made to conform to the curvature of the catheters *d'*, *e'* and furthermore it is to be noted that the longitudinal 35 edges of the guide bar *g*, both above and below the grooves therein, are rounded. Now in turning the rod *f*, the flattened end of the same will be turned in the same direction, likewise turning the guide bar *g*. The guide 40 bar *g* may thus be turned in the arc of a circle, and being pivotally connected to the end of the rod *f* at 20, may also turn about this point. It will now be apparent that if the rod *f* be turned from its normal position 45 after the catheters have been placed as shown in Figs. 4 and 5, assuming the direction of rotation to be clockwise, the guide bar *g* will be turned with the rod *f* and contacting with the catheter *e'* will also swing on its pivotal point 20 to a position shown in Fig. 6 or that in Fig. 7, which latter is extreme, thereby correspondingly deflecting the end of the said catheter, the amount of the deflection depending of course upon the angle through 55 which the rod *f* is turned, and because of the rounded longitudinal edges of the guide bar *g*, the same will automatically return to its normal position, by one edge contacting with and sliding over the surface of the telescopic 60 tube, when the rod *f* is returned to its initial position. The other catheter *d'* may be deflected and directed by turning the rod *f* counter clockwise.

It will be seen that from the construction 65 of the herein described instrument, the ends

of the catheters having been passed through the ureter canals into the kidneys, may be left there in position by withdrawing the instrument, so that the diagnosis may be certain in determining whether one or both 70 kidneys are diseased, and the catheter tubes as heretofore described, may be utilized to treat the diseased organ by forcing suitable specifics therethrough to the said organ.

I claim as my invention:

1. In a cystoscope, the combination with a telescopic tube, of means for conveying a catheter, means for engaging and directing the path of the forward end of the catheter, and means revolvably adjustable for actuating the last aforesaid means.

2. In a cystoscope, the combination with a telescopic tube, of means running parallel with and secured to the said telescopic tube for conveying a catheter, a rod revolvably mounted on the aforesaid means, and means operative upon turning said rod for engaging and directing the path of the catheter.

3. In a cystoscope, the combination with a telescopic tube, of a pair of tubes parallel 90 with each other and with the said telescopic tube and connected to the same and through each of which a catheter is passed, a rod journaled between the said pair of tubes, a guide bar pivotally connected to the said rod, and 95 means for revolvably adjusting the position of said rod to cause the said guide bar to engage and direct the path of the catheter in either of the said pair of tubes.

4. In a cystoscope, the combination with a 100 telescopic tube, of a pair of tubes parallel with each other and with the said telescopic tube and connected to the same and through each of which a catheter is passed, a rod journaled between the said pair of tubes, a 105 guide bar at the inner ends of said pair of tubes, means for pivotally connecting the said guide bar to the end of the said rod to cause the said guide bar to engage and direct the path of the catheter in either of the 110 said pair of tubes.

5. In a cystoscope, the combination with a 115 telescopic tube, of a pair of tubes placed side by side and parallel with the said telescopic tube and through each of which a catheter is passed, the outer ends of the said pair of tubes passing around the telescopic tube to the opposite side thereof, a rod journaled between said pair of tubes, a guide bar at the 120 inner ends of said pair of tubes, means for pivotally connecting the said guide bar to the end of the said rod to cause the said guide bar to engage and direct the path of a catheter in either of the said pair of tubes.

6. In a cystoscope, the combination with a 125 telescopic tube, of a pair of tubes placed side by side and connected to the said telescopic tube so as to run parallel therewith and through each of which a catheter is passed, a rod, bearings for the same secured between 130

the said pair of tubes, a guide bar pivotally connected to one end of the said rod and adjacent to the inner ends of the said pair of tubes, a head connected to the opposite end 5 of the said rod, a bearing connected to the said telescopic tube and in which the said head is journaled and a handle by which the said head and rod may be rotated to actuate the said guide bar.

10 7. A cystoscope comprising a sheath, having an outturned end member which together with the adjacent portion of the sheath, are provided with cut-away parts, a telescopic tube adapted to be passed into 15 and fit within the said sheath, of a pair of tubes placed side by side and connected to the said telescopic tube so as to run parallel therewith and through each of which a catheter is passed, a rod, bearings for the same 20 secured between the said pair of tubes, a guide bar pivotally connected to one end of the said rod and adjacent to the inner ends of the said pair of tubes, a head connected to the opposite end of the said rod, a bearing 25 connected to the said telescopic tube and in

which the said head is journaled and a handle by which the said head and rod may be rotated to actuate the said guide bar.

8. In a cystoscope, the combination with a telescopic tube, of independent means for supporting a pair of catheters in a parallel relation, a revoluble member interposed between the said means and a device for turning said member to engage either catheter to direct its path as desired and deflect the 30 respective catheter paths.

9. In a cystoscope, the combination with a telescopic tube, of a pair of parallel tubes for supporting a pair of catheters in a parallel relation, a revoluble member interposed between the said means and a device for turning said member to engage either catheter to direct its path as desired and deflect the 40 respective catheter paths.

Signed by me this 13th day of March, 1907. 45

REINHOLD H. WAPPLER.
